UNITED STATES PATENT OFFICE.

LORENZ KILLIAN, OF BROOKLYN, NEW YORK, ASSIGNOR TO PALMER & EMBURY MFG. CO.,
OF NEW YORK, N. Y., A CORPORATION OF NEW JERSEY.

DESIGN FOR A CHAIR.

No. 39,390.

Specification for Design.

Patented June 30, 1908.

Application filed May 15, 1908. Serial No. 433,141. Term of patent 7 years.

To all whom it may concern:

Be it known that I, LORENZ KILLIAN, a citizen of the United States, residing in the city of Brooklyn, in the county of Kings and State of New York, have invented a new, original, and ornamental Design for Chairs, of which the following is a specification, reference being had to the accompanying drawing, forming part thereof.

The figure is a perspective view of a chair showing my new design.

I claim:

The ornamental design for a chair, as shown.

LORENZ KILLIAN.
